DESIGN FOR A COMBINED ABRADING AND POLISHING MACHINE

Charles T. Oppermann, Detroit, Mich., assignor of one-half to Fred A. Oberheu, Lake Orion, Mich.

Application April 18, 1941, Serial No. 100,490

Term of patent 7 years

To all whom it may concern:

Be it known that I, Charles T. Oppermann, a citizen of the United States, residing at Detroit, in the county of Wayne and State of Michigan, have invented a new, original, and ornamental Design for a Combined Abrading and Polishing Machine, of which the following is a specification, reference being had to the accompanying drawing, forming a part thereof, in which:

Fig. 1 is a perspective view of a combined

abrading and polishing machine showing my new design;

Fig. 2 is a top plan view;
Fig. 3 is a front elevational view; and
Fig. 4 is a rear elevational view.

I claim:

The ornamental design for a combined abrading and polishing machine, substantially as shown.

CHARLES T. OPPERMANN.
